(57) **CLAIM**

The ornamental design for a fan frame as shown and described.

DESCRIPTION

FIG. 1 is a perspective view of a fan frame showing my new design;

FIG. 2 is another perspective view thereof;

FIG. 3 is a front view thereof;

FIG. 4 is a rear view thereof;

FIG. 5 is a right side view thereof;

FIG. 6 is a top plan view thereof; and,

FIG. 7 is a bottom plan view thereof.

The left side view is omitted since it is identical to the right side view. The gray scales shown in the figures represent the claimed portion of the design and do not represent any particular color and surface pattern. The broken lines, which show portions of the fan frame, form no part of the claimed design. The dot-dash lines in the figures represent an unclaimed boundary line and form no part of the claimed design.
